OIL SAVER

Filed May 3, 1929

UNITED STATES PATENT OFFICE

BENJAMIN P. HOFFMAN AND AYERS M. HOFFMAN, OF TULSA, OKLAHOMA, ASSIGNEES
TO PIERCE DEVELOPMENT COMPANY, OF TULSA, OKLAHOMA, A CORPORATION OF
OKLAHOMA

OIL SAVER

Application filed May 3, 1929. Serial No. 360,092.

This invention relates to oil savers particularly adapted for use in connection with oil wells.

Heretofore, it has been customary to provide an oil saver which comprised a housing adapted to be threaded on the upper section of well casing. This housing surrounded the cable on which the tools were suspended and packing was arranged in the housing 10 around the cable whereby oil could not escape. In this type of oil saver the housing had to be disengaged from the well casing in order to remove the tools from the hole and the saver often was quickly worn out by the action of the cable gradually cutting away portions of the housing.

An object of this invention is to provide an oil saver wherein the housing is provided with a removable liner whereby the tools may 20 be quickly run into or out of the hole without disengaging the housing from the well casing.

Another object is to provide a device of the type referred to wherein the liner is provided 25 with pockets in which suitable packing is arranged, the layers of packing being angularly arranged with respect to each other.

A further object is to provide a device of the type referred to wherein the housing is 30 provided with suitable openings adapted to align with the pockets in the liner, means being carried by the housing to force the packing into engagement with the well cable.

A further object is to provide a device of the type referred to wherein the housing is 35 provided with a plurality of openings adapted to receive packing followers, whereby the packing may be forced into engagement with the cable, the followers being movable 40 to a position within the housing which will permit removal of the liner.

A further object is to provide suitable cover plates for the openings in the housing, the plates being provided with threaded 45 openings through which the stem of the pack-

ing followers protrude whereby the followers may be actuated from without the housing.

A further object is to provide means for reducing friction to a minimum as the tools are run into and out of the hole, said means 50 also serving to guide the cable in its ascent and descent.

A further object is to provide means for sealing off the fluid between the liner and the housing. 55

Other objects and advantages of the invention will become apparent during the course of the following description.

In the drawings we have shown one embodiment of our invention. In this showing: 60

Figure 1 is a front elevation,

Figure 2 is a vertical transverse sectional view,

Figure 3 is a side elevation showing the liner withdrawn from the housing, 65

Figure 4 is a reduced sectional view taken substantially on line 4-4 of Figure 1, a part being shown in elevation, and,

Figure 5 is a perspective view of the packing. 70

Referring to the drawings the numeral 10 designates a preferably cylindrical housing provided with a longitudinal bore 11, upper openings 12 diametrically opposed to each other and lower openings 13 diametrically 75 opposed to each other. As shown, the lower openings are preferably somewhat smaller than the upper openings and are arranged at an angle thereto. The openings 12 may be covered by suitable plates

14 provided with axial threaded openings 15 and are secured to the housing by bolts 16 or the like. The lower openings 13 may be covered by plates 17 provided with an axial threaded opening 18 and are secured to the 80

housing by bolts 19 or the like. Preferably, the lower extremity of the housing is internally threaded as at 20 to receive the threaded portion of a coupling section 21

provided with an annular flange 22. A sleeve 85

90

23 is adapted to be threaded on to the uppermost section of well casing and the section 21 fits within this sleeve. A plurality of bolts 24 extend through the upper portion of the sleeve 23 and project above the annular flange 22 whereby the housing may be connected to the well casing 24'. Adjacent its upper extremity the housing is provided with an enlarged portion 25 a portion of which is internally threaded as shown at 26. Intermediate its ends the housing is provided internally with an annular tapered seat 27 for a purpose to be described.

Referring to Figures 2, 3 and 4 the numeral 28 designates a liner as a whole formed with a longitudinal bore 29 through which a cable 30 or the like is adapted to extend. The liner 28 is preferably formed of a pair of complementary sections 31 and 32 secured together by bolts 33 intermediate the ends of the liner and by bolts 34 threaded through ears 35 arranged adjacent the upper extremity of the liner. Each section of the liner is provided with substantially semi-annular transverse portions 36 and 37 connected by webs or ribs 38 whereby a pair of pockets 39 and 40 are provided in the upper portion of the liner. The pockets 39 and 40 form in effect a continuous opening transversely of the liner. Intermediate its ends each section of the liner is provided with a semi-annular tapered portion 41 and directly beneath the tapered portions, reduced semi-annular transverse portions 42 and 43 are provided, connected by webs or ribs 44 whereby a pair of somewhat smaller pockets 45 and 46 are provided. The pockets 45 and 46 form a continuous opening transversely of the liner and are angularly arranged with respect to the pockets 39 and 40, this angle preferably being 90°.

Adjacent its upper-extremity each section of the liner is provided with an enlarged semi-annular threaded portion 47 and on the top thereof the liner is provided with suitable bearings 48 in which are journaled rollers 49 adapted to engage the cable 30.

Packing members 50 and 51 are arranged in the pockets 39, 40 and 45, 46 respectively. The liner 28 is adapted to fit within the housing 10 and when in its proper position the pockets 39 and 40 will be in alinement with the openings 12 in the housing. At the same time the pockets 45 and 46 will also be in alinement with the openings 13 in the housing. As shown in Figure 2, packing followers 52 provided with threaded stems 53 are utilized to force the packing 50 into engagement with the cable 30. The stem 53 is threaded into the opening 15 in the plate 14 and any suitable connection may be made between the follower and its stem. As shown the inner extremity of the stem is reduced as at 54 and projects through an opening in the follower and the end of the stem is upset and

counter-sunk substantially as shown at 55. Packing followers 56 (see Figure 4) provided with stems 57 threaded in the openings 18 are adapted to force the packing 51 into engagement with the cable. The connection between the stem 57 and follower 56 is substantially the same as the connection previously described and need not be referred to in detail again.

The operation of the device is as follows:

The housing 10 is connected to a section of well casing by means of the section 21, sleeve 23 and bolts 24, as previously described. The tools are then suspended on the cable 30 by means of the rope socket 58 and complementary sections of the liner 28 are bolted together above the rope socket. The liner is then lowered into the housing and turned until the threaded portion 47 firmly engages the threads 26 in the housing and the pockets in the liner are in alinement with the respective openings in the housing. The followers 52 and 56 can then be utilized to force the packing into engagement with the cable 30 and prevent the leakage of oil along the cable. The arrangement of the upper and lower packing in angular relation forms an effective seal to prevent the leakage of oil. The inner extremities of the packing members do not quite touch when forced into engagement with the cable, but leakage through the openings between the inner extremities is prevented by reason of the angular arrangement referred to, as will be apparent. The tapered portion 41 of the liner engages the seat 27 in the housing and it will be apparent that a leak-proof joint will be provided between the liner and housing.

The packing may readily be replaced by removing the plates covering the openings 12 and 13 and removing the packing followers from the device. After new packing is inserted the followers will be returned to operative position, the plates put on and the packing forced into engagement with the cable, as will be understood.

When it is desired to remove the tools from the well it is only necessary to withdraw the packing followers into the openings 12 and 13 respectively without removing them from the housing. The liner is then turned to release the threaded portion and will be removed from the housing when the cable and tools are drawn upwardly. The rollers 49 tend to reduce friction to a minimum and serve as a guide whereby the tools may be quickly drawn into or out of the well. If desired the packing may be replaced when the liner is removed from the housing.

The entire device may be lifted with the tools if desired. This may be accomplished by leaving the liner in engagement with the housing and disconnecting the housing from the well casing.

It will be apparent that we have provided

an effective oil saver which will give indefinite service and will require replacement only of the liner and not of the entire device. The device is compact, may be made of relatively 5 light material and is inexpensive.

While we have described in detail the preferred embodiment of our invention it is to be understood that various changes in the size, shape and arrangement of parts may be 10 resorted to without departing from the spirit of the invention or the scope of the subjoined claims.

We claim:

1. An oil saver comprising a housing provided with openings therein and adapted to be secured to a section of well casing, a liner removably secured in said housing and provided with pockets adapted to aline with the openings in said housing, said liner being 20 adapted to surround a well cable, packing arranged in said pockets, and means operable through said openings for forcing said packing into engagement with said cable.

2. An oil saver comprising a housing provided with upper and lower diametrically opposed openings and adapted to be secured to a section of well casing, a liner removably secured in said housing and provided with transversely arranged upper and lower pockets adapted to aline with the openings in said housing, said liner being adapted to surround a well cable, packing arranged in said pockets on opposite sides of said cable, and means operable through said openings for 35 forcing said packing into engagement with said cable.

3. An oil saver comprising a housing adapted to be secured to a section of well casing, a liner removably secured in said housing, and adapted to surround a well cable, packing arranged in said liner and adapted to engage said cable, additional packing arranged beneath and at an angle with respect to said first named packing, and means for 45 forcing said packing into engagement with said cable.

4. An oil saver comprising a housing provided with upper diametrically opposed openings and lower diametrically opposed openings, the lower openings being angularly arranged with respect to the upper openings, said housing being adapted to be secured to a section of well casing, a liner removably secured in said housing and provided with 50 upper and lower transverse pockets adapted to aline with the openings in said housing respectively, said liner being adapted to surround a well cable, packing arranged in said pockets on opposite sides of said cable, and 55 means operable through said openings for forcing said packing into engagement with said cable.

5. An oil saver comprising a housing provided with openings therein and adapted to be secured to a section of well casing, a liner

removably secured in said housing and provided with pockets adapted to aline with the openings in said housing, said liner being adapted to surround a well cable, packing arranged in said pockets on opposite sides of 70 said cable, plates secured to said housing and adapted to cover said openings, each of said plates being provided with a threaded aperture, packing followers arranged adjacent said packing and provided with threaded stems adapted to rotate in the apertures in said plates to force said packing into engagement with said cable.

6. An oil saver comprising a housing provided with upper diametrically opposed openings and lower diametrically opposed openings, the lower openings being angularly arranged with respect to the upper openings, said housing being adapted to be secured to a section of well casing, a liner removably secured in said housing and provided with upper and lower transverse pockets adapted to aline with the openings in said housing respectively, said liner being adapted to surround a well cable, packing arranged in said pockets on opposite sides of said cable, plates secured to said housing and adapted to cover said openings, each of said plates being provided with a threaded aperture, packing followers arranged adjacent said packing and 90 provided with threaded stems adapted to rotate in the apertures in said plates to force said packing into engagement with said cable.

In testimony whereof we affix our signatures.

BENJAMIN P. HOFFMAN.
